COIL WINDING MACHINE

Chester H. Thordarson, Chicago, Ill.

Application February 24, 1930, Serial No. 430,845

6 Claims. (Cl. 164—65)

This invention relates to improvements in means and in the process for winding transformer coils and the like.

The main object of the invention is to provide a method and means for producing coils of mechanical and electrical uniformity at low cost and in large quantities.

By my invention sheet materials, such as sheet copper, is fed from a roll, cut into ribbons of the desired width and each ribbon fed to an individual arbor where it, together with the necessary insulation, is wound into a coil under uniform conditions of tension so that a uniform product is obtained.

15 Furthermore, by the use of my invention the machine may be simple, compact, easily adjusted and operated, and finished coils may be removed and new ones started with great ease.

One form of my invention is illustrated by the accompanying drawings, in which;

Figure 1 is a side elevation of the winding machine;

Fig. 2 is a view on an enlarged scale of a coil such as is produced by the machine;

25 Fig. 3 is a perspective view to illustrate the manner in which the stock sheet is fed into the machine and slit into ribbons;

Fig. 4 is a side elevation of the central portion of the machine shown in Fig. 1;

30 Fig. 5 is a plan section taken substantially on the line 5—5 of Fig. 1;

Fig. 6 is a transverse section of the machine taken substantially on the line 6—6 of Fig. 4;

Fig. 7 is an elevation of the feeding and slitting rolls;

Fig. 8 is a cross sectional fragmental view of the rolls;

Fig. 9 is a section taken through the axis of one of the winding shafts;

40 Fig. 10 is a cross section of the frictional driving connection for the winding shaft.

The machine illustrated by the drawings comprises, a frame consisting of a bed plate 2 which may be bolted to a supporting pillar 1, side plates 3, arms 3a, 4 and 24 for supporting the various parts. A roll of thin sheet copper or other conducting material, from which the coils are to be wound, is shown at 7 mounted so as to turn upon a shaft resting in open bearings 8. The sheet material is fed from this roll over guide roll 9 and under and over straightening rolls 10, through the tensioning device 11 to the feeding and cutting rolls 12 and 12a. There sheet material is cut into ribbons of the desired width by the rolls 12 and 12a and the selvage, which ordinarily

is somewhat damaged, trimmed off. Then one ribbon is led between guide rolls 21 to an arbor 33 on shaft 22. The next ribbon is fed in a similar way to an arbor 33a on shaft 22a, and so on, said arbors comprising the forms upon which the coils are wound. The edges or selvage of the sheet material which, as heretofore stated, is not generally suitable for use is fed between the same guide rolls 21 to a scrap reel 23.

The number of coils which can be wound simultaneously corresponds, of course, to the number of ribbons into which the copper sheet is cut by the feeding and slitting rolls 12 and 12a. The coils are spaced upon shafts 22 and 22a so that they are directly in line with the direction of travel of the respective copper ribbons as they come from the guide rolls 21. Shafts 22 and 22a are preferably mounted on opposite sides of the machine at equal distances from its vertical axis shown in Fig. 6, so that the length of each ribbon between the rolls 12 and 12a and the arbors 33 and 33a is substantially the same. In this way, whatever stretching occurs will be substantially the same for each ribbon, since, as will be hereinafter explained, the tension upon all of the ribbons is the same. The insulating material which is to be wound between the layers of copper ribbon is supplied from rolls 6 and 6a, one roll being provided for each coil and so spaced, as shown in Fig. 4, that each is in the same plane as the coil with which it relates. Tension upon the insulation is provided by tensioning devices 123, as shown in Fig. 6.

Uniform tension upon the sheet copper and the copper ribbons is obtained in the following manner:

As heretofore stated, the sheet copper before slitting passes through a tensioning device 11. This device consists of a plate 111 supported by frame 3 and a felt pad 13 which is held against plate 111 by a suitable backing plate 14 bolted to plate 111 at either end, as shown in Fig. 4. The copper sheet is passed between plate 111 and the felt pad 13, and in this way uniform tension is provided above the feeding and cutting rolls 12 and 12a.

Feeding and cutting rolls 12 and 12a each consists, as shown in Figs. 7 and 8, of a plurality of steel cutting discs 16, each of a width corresponding to the width of the copper ribbon and spaced apart by spacing rings 18 a corresponding distance. Spacing rings 18 are of a smaller diameter than cutting discs 16, and each of them is surrounded by a resilient ring 15 of rubber or suitable material, the outer diameter of which

is substantially equal to the outer diameter of cutting discs 16. As shown in Fig. 8, the cutting discs 16 of roll 12 are so positioned with respect to the similar cutting discs of roll 12a, that each disc is opposed by one of the resilient rings 15 and so that the edges of the cutting discs of one roll coact with those of the other roll to form a shearing device whereby the copper sheet may be cut into ribbons as it is fed into the rolls. In order to insure perfect shearing it is preferable, although not essential, that the cutting edges of the discs of one roll should pass between those on the other roll slightly. The resilient rings 15 grip the sheet securely, and thus a positive feed is insured under the tension determined by tensioning device 11. This arrangement provides an extremely efficient feeding and cutting means, the edges of the ribbons being very clean and smooth. This is a great improvement over the earlier forms wherein the material was pulled through the cutting device, since the tension is absolutely uniform and the ribbons cleanly cut and free from rough edges.

Fig. 3 illustrates diagrammatically the copper sheet cut into ribbons just after it has passed between the rolls 12 and 12a. This diagrammatic sketch illustrates the manner in which alternate ribbons are fed to the opposite winding shafts 22 and 22a and how the unused selvage passes downward to the scrap reel 23.

The course taken by the copper conductor and the insulation from the stock rolls to the winding shafts is now clear. There remains to be explained how motion is imparted to the several driven parts. A motor 37, mounted upon the supporting pillar 1, or in any other convenient position drives through a belt, large pulley 38. A sprocket wheel 39 positively attached to pulley 38 and, consequently, turning with it, drives through chain 40, large sprocket 41, rotatably mounted upon shaft 17. Another sprocket 41a attached to and upon the same shaft as sprocket 41 drives sprocket 42 which constitutes a part of a frictional drive device in which sprocket 42a is also included, and by means of which a uniform winding speed is imparted to shaft 22a controlled by the tension upon the copper ribbons rather than the speed of the motor.

Large sprocket 41 is duplicated upon the other side of the machine and cooperates with a duplicate set of parts identical to those just described to impart a similar controlled winding speed to the other winding shaft 22.

The friction drive of which sprockets 42 and 42a have been referred to as parts is shown in detail in Fig. 10. Sprocket 42 is freely mounted upon shaft 44. Its inner face is provided with one member 48 of a cone or other suitable clutch. Sprocket 42a is similarly freely mounted upon shaft 44 and carries the complementary member 49 of the clutch in its outer face. An adjustable pressure ring 53 provides a means whereby the pressure of the two clutch elements may be regulated through the nut 52. In this way, the small sprocket 42 may turn at one speed and the large sprocket 42a at another, so that the desired winding tension may be secured independently of the actual speed of the motor.

Scrap reel 23 may be driven, as shown in Fig. 1, from the same motor 37 by a belt 54 so loosely adjusted that it provides just sufficient tension to wind up the selvage as it is fed downward from the slitting roll.

Means is also provided whereby the finished

coils may be conveniently and quickly removed from the machine and new arbors substituted upon which to wind additional coils. In the lower ends of arms 24 of the frame are bushings 26 and 27, as shown in Fig. 9. One of these bushings, 27, is provided at its outer end with a bearing for the sprocket 30 which drives the winding shaft 22a. This sprocket rotates freely upon this bearing, being held in position by some such means as a set screw 31 engaging with an annular recess 32 in the bushing. The winding arbor 33 is provided with a longitudinal channel, through which shaft 22 may be passed and also with a key 35 which engages with a keyway cut in shaft 22 to lock the winding arbor to the shaft. Shaft 22 also projects through bearing 27 and into the hub of sprocket 30, where the same keyway engages with a key 36 to also lock the shaft to drive sprocket 30. By these means power applied to sprocket 30 will be transmitted to shaft 22 and to winding arbor 33, but at the same time shaft 22 may be readily withdrawn and winding arbor 33 with the coils thereon removed from the machine and a new arbor for additional coils put in its place.

It will be seen that in my device the conducting material in sheet form is fed under constant tension to and through the feeding and slitting rolls and to the winding rolls; that the length and tension upon each ribbon is the same so that each may be expected to stretch to the same degree; that by means of the frictional drive the tension under which the coils is wound is uniform and easily controlled; that the removal and replacement of the winding arbors may be effected with the greatest of ease and dispatch.

It will be understood that the drawings are for purposes of illustration only and disclose only one of a number of forms of my device and that many other forms are possible without departing from the scope of my invention.

It will also be understood that while I have shown for purposes of illustration a machine adapted for winding rectangular coils, any other shape of coils may be wound thereon simply by changing the shape of the arbor.

I claim:

1. In a sheet slitting and coil winding machine, a pair of composite positively driven rolls adapted to feed and slit sheet stock material into ribbons, a winding shaft associated with said rolls adapted to wind the ribbons into separate coils, a drive for said rolls, a frictionally driven connection from the rolls to said shaft, and means for adjusting the tension of said driving connection.

2. In a sheet slitting and coil winding machine, positively driven means for the combined feeding and slitting into ribbons sheet stock, means for maintaining a uniform tension upon the sheet, means for winding said ribbons into coils, and means for maintaining any desired tension upon the ribbons while winding them into coils.

3. In a sheet slitting and coil winding machine, a pair of power driven rolls for feeding and slitting into ribbons sheet stock, each consisting of a series of alternate concentric cutting and cushion rings, the cutting rings of one roll opposing the cushion rings of the other roll and slightly intermeshing with the cutting rings of the other roll, winding shafts, removable winding arbors on said shafts, a frictional drive from said rolls to said shafts, and means in said drive for maintaining any desired tension upon the ribbons while winding them into coils.

4. In a sheet slitting and coil winding machine, a pair of rolls for slitting sheet stock into ribbons, each roll being provided with cutter rings, cushion rings between the cutter rings, said cushion rings on one roll opposing the cutter rings on the other roll and having yieldable peripheral inserts, winding arbors for receiving the ribbons, means for driving said rolls, means for driving said winding arbors, and means for maintaining a uniform tension upon the ribbons being wound upon said arbors. 80
5. In a sheet slitting and coil winding machine, a pair of positively driven rolls for the combined feeding and slitting into ribbons of sheet stock, winding arbors for receiving the ribbons and winding them into coils, means for feeding in-
10
6. In a sheet slitting and coil winding machine, means for supporting a reel of sheet stock, a pair of cooperating feeding and slitting rolls for drawing the sheet stock from said means and slitting it into ribbons, a plurality of winding arbors for simultaneously winding the ribbons into coils, means for feeding insulating strips between the coil turns, and means for driving the rolls and arbors. 85
